[57] CLAIM

The ornamental design for bow for eyeglass frame, as
shown and described.

DESCRIPTION

FIG. 1 is a side perspective view of a bow for an eyeglass frame showing my new design, the frame front
being shown in broken lines for illustrative purposes
only;

FIG. 2 is a fragmentary side elevation view of the bow
on a greatly enlarged scale, the bow being fragmentarily
shown for convenience of illustration;

FIG. 3 is a fragmentary top plan view of the bow on a
greatly enlarged scale, the bow being fragmentarily
shown for convenience of illustration;

FIG. 4 is a side elevation view of the side of the bow
opposite that shown in FIG. 1; and

FIG. 5 is a bottom plan view of the bow.
